United States Patent Office

Des. 210,576

Patented Mar. 26, 1968

210,576

DOOR KNOCKER

Walter Koziol, Russell, Ill., assignor to Charmglow
Manufacturing Co., Antioch, Ill., a corporation of Illinois

Filed Nov. 13, 1967, Ser. No. 9,377

Term of patent 14 years

(Cl. D10—7)

The dominant features of my design reside in full lines.

What is claimed is:

The ornamental design for a door knocker, substantially as shown and described.
